UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM BOILER.

Application filed April 15, 1919. Serial No. 290,180.

Fig. 1 is a vertical transverse section through a boiler showing one embodiment of the invention; Fig. 2 a section on the plane of the line 2—2 of Fig. 1; Fig. 3 an enlarged section through the downtake headers to illustrate the method of staggering, and Fig. 4 a view similar to Fig. 1 illustrating certain modifications. Similar reference numerals indicate similar parts in the several views.

Referring to Fig. 1, the numeral 1 designates an upper bank of horizontally inclined water tubes, and 2 a corresponding lower bank shown as comprising three rows. The combustion chamber 3' below the lower bank of tubes extends substantially the entire length of the tubes, the boiler being fired at both front and rear by underfeed stoker mechanisms 3 of well known construction. The lower ends of the tubes of alternate vertical rows of the upper bank are connected to downtake headers 4 and 5, and the upper ends of said tubes are connected to uptake headers 6 and 7, while the lower ends of the tubes of alternate vertical rows of the lower bank are connected to header sections 8 and 9, and the upper ends of said tubes are connected with drop-leg extensions 6' and 7' of the uptake headers 6 and 7. The headers 4 and 5 are connected to the header sections 8 and 9, respectively, by relatively long nipples 10 and 11, and the upper ends of the headers 4 and 5 are connected to a transverse steam and water drum 12 by nipples 13 and 14 which are preferably substantially straight and parallel as illustrated. All of the headers are preferably sinuous in form in the planes of the headers of the respective rows, as indicated in Fig. 1. Said drum is also connected to the uptake headers 6 and 7 by two rows of horizontal tubes 15. A baffle 16 extends over the upper row of tubes 2 from the header sections 8 and 9 for a portion of their length, and a transverse baffle 17 divides the upper bank of tubes into two passes so that the gases will flow over the banks of tubes in the general direction indicated by the arrows to the outlet connection 18, the latter delivering the gases to an uptake flue in which is located an economizer comprising a series of horizontal boxes 19 connected by tubes 20. This economizer may constitute the high pressure stage of an economizer system, the low pressure stage of which is not shown in Fig. 1

but is shown in Fig. 4. The tubes and boxes of the economizer shown in Fig. 1 are preferably of wrought iron or wrought steel to withstand the high boiler pressure to which they are subjected. As shown, it is divided into three sections, water entering the uppermost section through the pipe 21 and leaving said section through the pipe 22, by which the water is delivered to the middle section and leaves the latter through the pipe 23, which delivers it to the lowermost section, from which the water flows through a pipe 24 to the steam and water drum 12.

By arranging the economizer in the way described, the advantages of the counterflow principle are secured as the uppermost of the three sections which comes in contact with the coolest gases will contain the coolest water, the middle section which comes in contact with the gases of an intermediate temperature somewhat hotter water, and the third and lowermost section which comes in contact with the hottest gases will contain the hottest water. Each section is fed at the lower part and the heated water passes away from the upper part. This results in the water flowing upwardly throughout each section which gives a more even distribution between the different tubes than should the water be fed downwardly through the sections. Again, by feeding the water upwardly throughout each section in the way described the water flowing through each tube flows in a slightly upward direction and tends to more thoroughly sweep out any air or contained gases from the tubes than would be the case should there be a downward flow.

In the form shown in Fig. 1, a primary superheater 25 is located in the triangular space above the upper bank of tubes, and a secondary superheater 26 is located in the secondary combustion chamber between the two banks of tubes, the steam from the drum 12 being delivered through the pipe 27 to the superheater 25 and from the latter through a pipe 28 to the upper box of the superheater 26. The superheated steam is delivered to the main through a connection from the lower box 26' of the superheater 26. A second superheater 29 is also located in the secondary combustion chamber between the two banks of tubes, to the upper cross-box of which steam is delivered from one of the stages of a steam turbine, and the steam so re-superheated, returned through a con-

nection from the cross-box 29' to a lower pressure section of the turbine. All of these superheaters comprise cross-boxes connected by U-tubes and all are arranged with their upper legs substantially horizontal so that they can be flooded and drained. Also, the loops for the superheaters 26 and 29 should be so proportioned that they can be introduced by passing them between the nipples 10 and 11.

One of the essential features of the construction described is the staggered arrangement of the headers whereby headers having a greater width than the distance between the tubes measured horizontally may be employed, and thus enabling the use of a heavier construction of header for a given tube diameter than is possible where the headers are arranged in the same plane. For example, if a boiler for exceptionally high pressure is desired, a header that would normally be used for a four-inch diameter tube could be made of the same outside dimensions but with thicker walls and could be employed for a three-inch tube. Should all of the headers when constructed in this way be placed in the same plane, the spaces between the three-inch tubes for the passage of the gases would be wider than they should be for the best operation and efficiency. By overlapping the headers the proper spaces for the passage of the gases is secured between the tubes. With the staggered and overlapping arrangement of the headers I provide means for calking the spaces between the headers to secure a gas-tight joint, as by placing asbestos or other plastic material 48 between the headers and holding such material in position by special pieces 49, in the form of angle irons, bent to fit the stagger of the headers. The pieces 49 may be held by fluted struts 49^a, which, after being placed in position and being struck, will be extended and made to bear tight against the pieces 49.

Another feature of the described arrangement is that where the gases are taken off between the two banks of tubes, as in Fig. 1, the staggered arrangement of the nipples 10 and 11 can be secured with straight nipples instead of using curved nipples, as described in a companion application. Also, the staggered arrangement of the nipples 13 and 14 which connect the steam and water drum 12 with the headers 4 and 5 results in the cutting away of a less amount of metal in a longitudinal line measured along the drum, thereby giving greater strength for a given drum thickness than is possible with all of the nipples arranged in the same plane.

In Fig. 4 I have shown a modified arrangement in which the tubes of the bank 1 are connected to inclined instead of vertical headers, as in Fig. 1, the nipples 10 and 11 also being inclined, and in which I secure

the same advantages in the staggered arrangement of the headers and nipples as described in connection with Fig. 1. The bank is here shown as divided into three transverse passes by baffles 30 and 31, the former being vertical so as to provide a gradual reduction of area for the flow of the gases, and the latter being inclined so as to provide an opening at the top of the second pass of substantially the same area as the opening at the top of the first pass. The gases take the general course indicated by the arrows and leave the boiler between the staggered row of nipples 13 and 14 which connect the downtake headers and the steam and water drum. The area for the flow of the gases and between the nipples should be at least the same as that between the boiler tubes at the top of the third pass. In practice, if the distance between the center lines of the tubes of each row of nipples is twelve inches, and corresponds to the spacing between the boiler tubes six inches apart, the spaces between the tubes of each row of nipples for the flow of the gases for tubes 3" in diameter will be nine inches.

After the gases leave the boiler they enter the outlet connection 18' and flow over the tubes of a high pressure stage of an economizer system, which, as here shown, comprises rows of vertical tubes 32 connected to lower and upper boxes 33 and 34, these boxes having hand-hole fittings provided for every four tubes. The boxes 33 are connected to a cross-box 35, through which the water from the low pressure section of the economizer enters, the water flowing upwardly through the tubes to the boxes 34 and then into a cross-box 36, from which it flows to the steam and water drum 12. The gases are made to flow across the tubes 32 by cross baffles 37 which extend about two-thirds of the way across the full width of the economizer. These cross baffles are preferably made of cast iron plates and need not be perfectly tight, as they serve merely as deflectors to throw the gases from one side to the other. The economizer tubes are kept clean by means of rotary soot blowers 38 passing in from the rear, as indicated.

The gases, after leaving the high pressure stage of the economizer, flow through a horizontal flue 39 in which is located the low pressure stage of the economizer, such stage, as here shown, consisting of three banks of vertically arranged tubes 40 fitted into horizontal boxes or headers, the tubes and headers preferably being of cast iron. The tubes of the several banks are so connected that the water entering through pipe 41 is distributed through the lower connected headers of the right-hand bank, and from said bank, flows in succession through the other banks to the outlet pipe 42, through which it may be delivered to a tank,

not shown, to effect the disengagement and escape of the air and gases from the water. The water, if such tank is used, is pumped to the high pressure section through a pipe 5 leading to the cross-box 35.

Beneath the low pressure stage of the economizer are hoppers 43 for collecting soot deposited from the gases, and that which may be removed from the exterior of 10 the tubes by scrapers 44. A suitable hopper 45 is also shown under the high pressure stage of the economizer.

The gases are drawn from the boiler through the economizer stages by a suction 15 fan 46. In this particular arrangement the boiler is shown as fired by a travelling stoker 47.

The steam from the boiler is led by the pipe 27 to the superheater in the triangular 20 space above the upper bank of tubes, the superheater shown comprising two double loops of U-tubes, the steam entering the box 48 and leaving by the box 49 to the steam main. The steam from one of the nipples 25 of the turbine is re-superheated in the superheater 29 in the secondary combustion chamber between the two banks of tubes, as in Fig. 1. The gases are directed to the uptake pass of the tubes by the baffle 16 and by the 30 baffle 50 between the superheater boxes, as indicated in both Figures 1 and 2.

What I claim and desire to secure by Letters Patent of the United States is:—

1. A water tube boiler comprising a bank 35 of generating tubes, headers to which said tubes are connected, said headers being arranged in rows and those of one row staggered relatively to those of the other row, calking in the spaces between the headers 40 to secure a gas-tight joint, and retaining members to hold the calking material in position.

2. A water tube boiler comprising a bank 45 of generating tubes, headers to which said tubes are connected, said headers being arranged in rows and those of one row staggered relatively to those of the other row, members bent to fit the staggers of the headers, calking between said members and the 50 headers, and retaining members bearing against said bent members.

3. A water tube boiler comprising two banks of tubes spaced apart, downtime and

uptake headers to which the tubes of the respective banks are connected, said downtime 55 headers being arranged in staggered relation, nipples connecting the two sets of downtime headers, said nipples being also arranged in staggered relation, and an outlet flue into which the gases are discharged 60 between said nipples.

4. A water tube boiler comprising two banks of tubes spaced apart, downtime and uptake headers to which the tubes of the respective banks are connected, said downtime 65 headers being arranged in staggered relation, a transverse baffle in the upper bank of tubes, nipples connecting the two sets of downtime headers, said nipples being also arranged in staggered relation, and an outlet 70 flue connecting with the down pass of the upper bank of tubes and arranged to lead the gases across said staggered nipples from between the banks of tubes.

5. A water tube boiler comprising spaced 75 headers connected by water tubes, the headers at one end at least of the tubes being arranged in staggered relation, a water chamber, connections including nipples from the last mentioned headers to said water 80 chamber, and an outlet flue into which the gases are discharged between said nipples.

6. A water tube boiler comprising spaced 85 headers connected by water tubes, the headers at one end at least of the tubes being arranged in staggered relation, a water chamber, connections including substantially straight parallel nipples from the last mentioned headers to said water chamber, and an outlet flue into which the gases are dis- 90 charged between said nipples.

7. A water tube boiler comprising a drum and spaced headers connected by water tubes, the headers at one end at least of the tubes being arranged in staggered relation, 95 nipples connected at one end to said staggered headers and arranged in staggered and parallel relation, said nipples being connected at their other ends to said drum, and a superheater located within the boiler 100 setting in a space defined in part by said nipples the tubes of which are adapted to be withdrawn between said nipples.

In testimony whereof I have hereunto signed my name.

DAVID S. JACOBUS.
